METHOD FOR MAKING TUBES

Bert L. Quarnstrom, Detroit, Mich., assignor to
 Bundy Tubing Company, Detroit, Mich., a corporation of Michigan

Application October 14, 1938, Serial No. 235,953

3 Claims. (Cl. 113—33)

This invention relates to a method for making tubing from strip metal stock, and it has to do particularly with the making of plural ply tube from a plurality of strips of stock.

5 The invention may be exemplified by a description of the making of double ply tube from two strips of stock. One strip, which may form the inner ply of the tube, is moved longitudinally and is fashioned into tubular form with a longitudinally running seam. The edges of the strip are brought together at the seam, and the edges may be brought together in abutting relationship. In order to keep the edges together, prior to ultimate completion of the tube, the 10 inner strip is so fashioned that the metal, measured circumferentially, is slightly in excess of that required to complete the tubular form, and when the edges are urged into abutting relationship the metal is stressed. This stress holds the 15 edges in closely abutting relationship. The other strip, which may form the outer ply, is moved longitudinally with like movement, and is fashioned into tubular shape around the tubular form of the inner ply. The strip for the outer ply is 20 so bent or fashioned that certain portions are given a curvature on a radius shorter than the radius which is taken in the completed tube, and in such a manner that the edge portions of the outer ply frictionally grip the inner ply so that 25 the edges of the outer ply remain in proper seam forming relationship prior to the ultimate securing of the edges and plies together. With the tube thus formed, the seams and plies are united by a metal which is rendered molten.

30 In the drawings:

Fig. 1 is a view illustrating, somewhat diagrammatically, an apparatus and a method for making tubing in accordance with the invention.

Fig. 2 is an enlarged cross sectional view of the strip for forming the inner ply, taken substantially on the line 2—2 of Fig. 1.

Fig. 3 is an enlarged cross sectional view taken substantially on line 3—3 of Fig. 1, showing the first forming operation on the inner strip.

Fig. 4 is an enlarged view taken substantially on line 4—4 of Fig. 1, showing the second forming operation on the inner strip.

Fig. 5 is an enlarged sectional view taken substantially on line 5—5 of Fig. 1, showing the third forming operation of the inner strip.

Fig. 6 is an enlarged sectional view taken substantially on line 6—6 of Fig. 1, showing the fourth forming operation on the inner strip.

Fig. 7 is an enlarged sectional view taken substantially on line 7—7 of Fig. 1, showing the fifth

and final forming operation on the inner strip.

Fig. 8 is an enlarged sectional view taken substantially on line 8—8 of Fig. 1 showing a preliminary operation which may be performed on the outer strip.

Fig. 9 is an enlarged sectional view taken substantially on the line 9—9 of Fig. 1 showing the first forming operation on the outer strip.

Fig. 10 is an enlarged sectional view taken substantially on line 10—10 of Fig. 1 showing the second forming operation on the outer strip.

Fig. 11 is an enlarged sectional view taken substantially on line 11—11 of Fig. 1 showing the final forming operation.

Fig. 12 is an enlarged composite view illustrating the several forming operations on the inner strip, said view being of sectional nature but with some parts not cross hatched for the purpose of clearness.

Fig. 13 is an enlarged composite view similar to Fig. 12 showing the several forming operations on the outer strip.

The strip stock from which the tube is made may be ferrous metal which is coated or plated with a sealing metal such as low or high fusing point solder, as for example, a solder comprising lead and tin or a solder comprising cuprous metal. Other sealing metals or solders may be used as long as the solder or sealing metal melts or fuses at a temperature lower than that of the strip. Also, other metals may be used in the strip. The strip stock which forms the inner 30 ply, may be drawn from a reel 2 and it is passed through a tube mill comprising a series of forming rolls. The first set of rolls 3, as shown herein, forms the strip into a rather open U-shaped form, as shown in Fig. 3. The second set of rolls 4 continues this forming as shown in Fig. 4. The third set of rolls 5 further progresses the forming of the strip substantially into U-shape, as 35 shown in Fig. 5. The eight portions of the form shown in Figs. 3, 4 and 5 are on a radius substantially the same as the radius upon which this portion of the metal which will lie in the finished tube. The next set of rolls shown at 6 closes in 40 the U-form as shown in Fig. 6, preferably leaving the edge portions of the strip substantially straight. The next set of rolls 7 brings the edge 45 portions together and completes the forming operation on the inner strip as shown in Fig. 7. 50

At this point it is thought well to describe the forming operations on the outer ply and to then later revert to a detailed description of the particular shape which is given to the inner ply and the function thereof. A strip 26 which forms 55

the outer ply may be drawn from a reel 21 and, as shown herein, is passed between pressure rolls 8 which bevel the edges of the strip, as illustrated at 22 (Fig. 8). The outer strip may then 5 be directed over a guide roll 23 and through a die 24, the formed inner ply also passing through this die. The formed inner ply and the outer strip then pass through forming rolls; one set of rolls is shown at 9, which performs an operation 10 on the outer strip giving it a shape substantially as shown in Fig. 9. The formed inner strip and outer strip then pass between a set of rolls 10 which may be placed on axes perpendicular to the axes of the rolls thus far described and 15 fashion the edge portions of the outer ply to a position, as substantially illustrated in Fig. 10. The formed inner ply and the outer strip then pass between a set of forming rolls 11 similar to Fig. 10, which completes the forming operation 20 of the outer ply, as substantially illustrated in Fig. 11.

Thus a tube is formed from two strips of stock having double ply walls with the inner ply having its edges disposed in a butt seam 25 and with 25 the edges of the outer ply in a scarfed seam 26. The particular type of seams may vary as, for example, the edges for the outer ply may be arranged in a butt seam, but the preferred arrangement is that the seams be as shown herein. The 30 composite tube structure may then pass through a series of rolls 12, 13 and 14 which may apply pressure to the tube structure. It will be understood that some of the rolls of the tube mill and some of the pressure rolls may be driven in order 35 to propel the strips and tubular form therethrough. The number of forming rolls used on the inner strip and on the outer strip may vary, thus varying the number of forming steps, as such variations may be desirable or necessary with strip stock of various metals, thicknesses, 40 widths, etc.

The tube may then be completed by a heat treatment to melt the coating or plating metal and cause the same to fuse and thus unite the 45 plies and seams. Such an arrangement is dia- 50 grammatically illustrated in Fig. 1 where elec- 55 trodes 15 and 16 are connected to one side 17 of a transformer for the heating current, and elec- 60 trodes 18 are connected to the other side of the 65 transformer. With this arrangement there is no potential between the outside electrodes 15 and 16, with the result that current flows through the section of tube between electrodes 15 and 18 and between electrodes 16 and 18. Since there is no 70 potential between electrodes 15 and 16, the remaining part of the apparatus such as the tube mill and pressure rolls, need not be insulated. This is but one manner of heating the tube; other heating means such as furnace structures may be used through which the tube may be passed. It is 75 within the invention to carry the sealing metal into position in a form other than the form of a plating or coating on the strip stock itself although so far as this disclosure is concerned, it appears sufficient to make specific reference only 80 to this one manner of carrying the sealing metal into position. It will be understood that after the tube is heated for the fusing of the sealing metal that it is properly cooled and, if necessary, 85 the tube may be confined in a neutral or reducing atmosphere while in heated form.

A problem in the making of a tube of this character is that of maintaining the edges of the strips tightly together prior to the sealing 90 of the tube with molten metal and also in main-

taining the inner and outer plies in engagement with each other.

In Fig. 12, the several shapes assumed by the inner ply are shown and particular reference is made to the shape of the strip in that form 5 shown in Fig. 6. In this condition the portions of the strip adjacent the edges are substantially straight although they may have some curvature. The radius of the curvature, however, from substantially the points *x* to the points *y* is less 10 than the radius taken by this portion of the metal in the finished inner ply. Accordingly, when the strip is in the shape shown in Fig. 6, the metal on each side of the form from substantially the point *y* to the point *x*, as well as some of the straight 15 metal beyond the point *x*, lies radially inwardly of the position which this metal is to assume in the finished inner ply. Therefore, when the edges of the strip are brought together in abutting relationship, as illustrated in Figs. 7 and 12, the metal 20 of the strip is placed under stress. This stress causes the edges to come into close abutting relationship under pressure and are held in engagement by the force exerted by the stressed metal. As a result, the inner ply is self shape retaining 25 and the abutting edges remain in abutting relationship so as to properly receive the molten metal which will flow between the edges and seal the same. In other words, the situation may be viewed as one where the over-all distance from 30 the points *y* to the edges, while in the Fig. 6 form, is greater than that required from the points *y* to the butt seam to complete the formation of the inner ply into the form shown in Fig. 7.

The first forming operation on the outer strip, as indicated in Figs. 9 and 13, places a curvature in the strip where the strip overlies the butt seam of the inner ply, and from about the points *a* to the points or edges *b* of the strip, the stock is given a radius somewhat less than the radius 35 this stock will assume in the finished tube. The intermediate portions between the curved form in the center portion of the outer strip and the points *a* may remain rather straight. Thus a tube is formed from two strips of stock wherein the strip forming the inner ply is self shape retaining, with its edges maintained in engagement by stress in the metal, and wherein the strip forming the outer ply is self shape retaining, the stress in the metal holding the outer ply contiguous to the inner ply substantially throughout the circumferential extent and holding the edges in tight engagement by the force exerted due to the stress in the metal. The tube thus formed is capable of maintaining its own shape during that temporary time between the completion of the forming of the tube and the time when the sealing metal unites the plies and seams. It will be appreciated, of course, if the plies or seams are not close together that the sealing metal will not properly unite and seal the same.

I claim:

1. The method of making plural ply tube from a plurality of strips of metal stock wherein the plies and seams are united by fused sealing metal; the steps comprising fashioning one strip into an inner ply of hollow cross sectional form, fashioning and setting portions of an outer strip adjacent its edges, on radii shorter than the radius of the outer ply in the finished tube, fashioning the outer strip around and contiguous to the inner ply with pressure to stress the metal of the outer ply incident to the resultant increase of the said radii of curvature of said portions, which stress causes the edge portions of the outer strip to frictionally engage the inner ply, whereby the outer ply is self shape-retaining upon the inner ply.

2. The method of making plural ply tube from a plurality of strips of metal stock wherein the plies and seams are united by fused sealing metal;

the steps comprising fashioning one strip into an inner ply of hollow cross sectional form, with a longitudinally extending seam, fashioning and setting the edge portions of an outer strip, which is to form an outer ply, on radii shorter than the radius of the outer ply in the finished tube, fashioning the outer strip around the inner ply and bringing the edge portions thereof into seam-forming relationship at a point circumferentially removed from the seam of the inner ply, to stress the metal of the outer ply incident to the increase of said radii of curvature of said edge portions, as the said portions so curved are brought into contiguous relation with the inner ply, whereby the stress in the metal causes the edge portions of the outer ply to frictionally grip and to remain fixed upon the inner ply.

3. The method of making plural ply tube from a plurality of strips of metal stock wherein the plies and seams are united by fused sealing metal; the steps comprising fashioning one strip into an inner ply of hollow cross sectional form, beveling the edges of a strip for forming the outer ply, fashioning and setting portions of said outer strip adjacent its edges on radii shorter than the radius of the outer ply in the finished tube, fashioning the outer strip around and contiguous to the inner ply and bringing the beveled edges together into a scarfed seam, to stress the metal of the outer ply incident to the resultant increase of the said radii of curvature of said portions, which stress causes the edge portions of the outer strip to frictionally engage the inner ply, whereby the outer ply is self shape-retaining upon the inner ply.

BERT L. QUARNSTROM.
